UNITED STATES PATENT OFFICE.

EDWARD F. KING, OF PROVIDENCE, RHODE ISLAND.

FABRIC AND METHOD OF MAKING THE SAME.

Application filed November 16, 1920. Serial No. 424,492.

To all whom it may concern:

Be it known that I, EDWARD F. KING, a citizen of the United States, residing at Providence, in the county of Providence and State of Rhode Island, have invented certain new and useful Improvements in Fabrics and Methods of Making the Same, of which the following is a specification.

My invention relates to rubberized fabrics adapted for use in tires, shoe heels and for other purposes.

In such fabrics it has heretofore been customary to apply the rubber element exclusively to the exterior of the constituent strands of the fabric which has resulted in an insufficient and irregular application of the rubber and a consequent lack of adhesiveness of the strands and a want of tensile strength in the resultant fabric. The usual methods of applying the rubber to the strands has also rendered the fabric surface sticky and difficult to handle prior to the stage of vulcanization.

The essential objects of my invention are to overcome the enumerated disadvantages and to cheapen construction, and prevent peeling of the rubber, and prevent chafing of the strands.

To the above ends essentially my invention consists in such parts, and in such combinations of parts, and in such steps, and in such successions of steps as fall within the scope of the appended claims.

For the purpose of illustrating my invention there is shown in the accompanying drawings, which form a part of this specification, the form thereof at present preferred although the various steps and instrumentalities of which my invention consists may be variously performed and embodied without departing from the spirit of my invention.

Figure 1 is a perspective view of a broken away portion of a length of sheather strand,

Figure 2, a longitudinal central section of three strand portions assembled side by side before compressing,

Figure 3, a like section of the same after compression,

Figure 4, a section on line 4-4 of Figure 3, and

Figure 5, a plan view of a section of the complete fabric.

Like reference characters indicate like parts throughout the views.

The showing of the drawings is for illustrative purposes largely diagrammatical, and the constituent parts of the fabric are exaggerated in thickness and conventionalized.

In carrying out my invention a core 10 of soft rubber of any desired cross sectional outline is loosely surrounded in a textile casing or sheath 11. This casing may be either a woven or braided fabric but superior results are attained by the latter. In the braided sheath, as shown in Figure 1, the constituent strands 13 diagonally cross each other, passing alternately over and under each other successively in the manner characteristic of a braided fabric to form the tube. As usual in a braid the fabric strands adjacent their points of crossing each other are necessarily not in as close contact with each other as elsewhere. This results in interstices 14 at these points. The resultant interstices in a woven fabric while present are less pronounced.

After encasing the rubber core or strand 10 in its sheath, several lengths of the structure shown in Figure 1 are arranged side by side, as shown in Figure 2, and then compressed between two flat plates or dies while being subjected to heat sufficiently intense to liquefy the cores 10. The liquid rubber of the cores during this operation exudes outwardly through the sheaths 11 including the interstices 14, and broadens and flattens the lengths. The rubber thus not only fills the interstices as at 16 but the exuded liquid forms films or skins 18 upon the upper and lower faces of the resultant fabric, and deposits material 20 in the spaces between the flattened sheath, and material 22 exterior of the exposed sides of the sheaths.

After the heat and pressure have been discontinued the rubber hardens and completes the fabric strip 24 shown in Figure 5.

A tire, heel, or sheet of the fabric, may be built up of any desired number of layers or units in any usual or approved way, but preferably with the sheathed cores crossed in alternation. Such a built up structure has the characteristics of the single-ply fabric shown; that is to say, the sheath and core are intimately united in every direction by reason of the ready permeability of the sheath and the plasticity of the core under heat and pressure, so that not only the adjacent units but also those superposed

are completely and inseparably tied or bound together, in a thoroughly homogeneous state.

By the use herein of the word "flat" and its derivatives, I do not mean to limit the invention to the shape of the product, since obviously the invention is capable of use in articles having a great variety of shapes.

I claim:

10. 1. The herein described method of forming a fabric consisting in enclosing a soft rubber core in a permeable, interstitial textile sheath, arranging a series of lengths of the same in parallelism adjacent each other, and subjecting the thus arranged lengths to heat and pressure and thereby softening the core and spreading its substance through the sheath and uniting the lengths in a homogeneous fabric.
20. 2. The herein described method of forming a fabric consisting in surrounding a soft rubber core with a braided sheath provided with interstices between its strands, assembling a plurality of lengths of the same side by side, and finally subjecting the assembly to heat and pressure and thereby diffusing the plastic core through the interstices and

uniting the assembled lengths in a homogeneous mass.

3. The herein described method of forming a fabric consisting in braiding loosely around a continuous soft rubber core a fabric sheath, separating the same into lengths, assembling the lengths side by side, softening the rubber core by heat, and compressing the lengths to force the material of the cores through the adjacent sheaths and form a continuous rubber external covering for the resultant compound fabric.

4. In a fabric, a plurality of lengths comprising soft rubber cores and permeable interstitial textile sheaths therefor, the rubber of the cores interpenetrating the sheaths, and a soft rubber casing connecting and surrounding the lengths.

5. In a fabric a plurality of lengths comprising soft rubber cores and braided, permeable, sheaths surrounding the cores and provided with interstices, and a soft rubber casing surrounding the sheaths and connected with the cores through the interstices.

In testimony whereof I have affixed my signature.

EDWARD F. KING.
